UNITED STATES PATENT OFFICE.

FREDERICK STARR, OF ROCHESTER, NEW YORK.

DESIGN FOR CAST-IRON LEGS OF PIANO-FORTES.

Specification forming part of Design No. 633, dated February 28, 1854.

To all whom it may concern:

Be it known that I, FREDERICK STARR, of the city of Rochester, county of Monroe, and State of New York, have invented or produced a new and original ornamental Design for a Cast-Iron Piano-Forte Leg; and I do hereby declare that the following is a full and exact description of the same, reference being had to the annexed drawings and letters of reference marked thereon, in which—

Figure 1 shows an elevation of one side of my piano-forte leg. The other side is precisely the same as shown at Fig. 1. Fig. 2 shows a section through A B, Fig. 1.

C, Fig. 2, shows the projection shown at C, Fig. 1.

D, Fig. 2, shows the circular surface of the leg shown at D, Fig. 1.

E, Fig. 2, shows a section of the projection shown at E, Fig. 1.

F, Fig. 2, shows the projection shown at F, Fig. 1.

G, Fig. 2, shows a section at G, Fig. 1.

H, Fig. 2, shows a section of the leaf shown at H, Fig. 1.

I, Fig. 2, shows a section of the projection shown at I, Fig. 1.

What I claim as my invention or production, and desire to secure by Letters Patent, is—

The ornamental design of a cast-iron piano-forte leg, substantially as herein described and represented.

FREDERICK STARR.
